WILLIAM W. WILSON, OF LOS ANGELES, CALIFORNIA.

ROTARY WELL-BORING APPARATUS.

1,198,803.

Specification of Letters Patent. Patented Sept. 19, 1916.

Application filed July 16, 1914. Serial No. 851,363.

To all whom it may concern:

Be it known that I, WILLIAM W. WILSON, a citizen of the United States, residing at Los Angeles, in the county of Los Angeles and State of California, have invented new and useful Improvements in Rotary Well-Boring Apparatus, of which the following is a specification.

This invention relates to rotary well boring apparatus such as employed for drilling oil and other wells, in which rotary motion is imparted to the boring bit or tool through a string of pipe, or the like, from a rotary top or table installed at the orifice of the well hole and is in turn rotated by a suitable prime mover or drive means between such prime mover and the table. Various operative conditions tend to cause such rotary tops or tables to become lifted or misplaced from their true zones or planes of rotation, principal among which causes is the tendency of the tables to "climb" upon the rotating means which are usually applied beneath the table or a portion thereof, and consists usually of an annular series of beveled teeth to and beneath which is applied a suitably driven bevel gear. To prevent such displacement or tendency to shift and move out of proper working position, devices or means known as holding down means are usually employed, a common form of which is a knee plate or angular piece connected with the base frame upon which the table rotates and suitably engaged with the table, either within the central opening thereof or at the outer rim thereof, so as to keep the table properly located in rotation, the engagement being such that rotation is not interfered with, and only a varying degree of frictional loss results.

It is the object of the present invention to provide means for operating and holding in position a rotary table or top whereby any tendency of the table to become shifted or misplaced will be opposed if not altogether eliminated; and to obviate the necessity of means specifically provided for holding the table down in its proper path of rotation. With this end in view, I provide a rotary drive for the table which is an underneath rather than an overhead drive, so that any tendency of the parts of the drive upon the table to slip or creep upon the parts of the drive which coöperate therewith will cause a resultant tendency of the

table to be depressed. This depression being opposed by the mounting of the table, it results that the table remains in its proper plane of rotation; and therefore no holding down means *per se* is required to that end. 60 The table thus rotates in its true zone, and properly coöperates with the string of pipe, through the means whereby the latter is united in rotative couple with the table, any tendency of the pipe or said latter means to 65 become jammed in the table being thus eliminated; and the string of pipe being free to play vertically through the table as the well hole is developed.

With the above and other objects in view, 70 and the above means as generally set forth entering into the embodiment thereof, the invention consists in the novel and useful provision, formation, construction, combination and relative arrangement and association of parts, members and features, all as hereinafter described, shown in the drawing and finally pointed out in the claims. 75

In the drawing: Figure 1 is a central vertical and partly fragmentary sectional elevation through a rotary table or top of well boring apparatus and a portion of a string of pipe, means being shown for uniting the string of pipe with the table in rotative couple, and means being provided for 80 rotating the table and holding it in proper working position in accordance with the invention; and Fig. 2 is a horizontal transverse sectional view of the same, taken upon the line x^2-x^2 , Fig. 1, and looking in the 85 direction of the appended arrows. 90

Corresponding parts in both the figures are designated by the same reference characters.

Referring with particularity to the drawing, A designates a conventional form of rotary top or table, which is shown as mounted upon a suitable base frame B, for rotation, suitable anti-friction devices or rollers b being interposed between the table 100 and the base frame as direct supports for the table.

D designates a portion of a length of pipe shown as extended through the customary central opening in the table, and E designates means uniting the table and the portion of the string of pipe D in rotative couple. It is to be understood that the boring tool or bit is rotated by the string of which the portion D is shown, being con- 110

nected with the lower end of the string and in the hole, the upper portion of which latter is designated at F.

G designates drive means for rotating the table A, the same including a member g which is directly driven from a suitable prime mover, and a member h upon the table with which the member g coöperates.

The anti-friction devices b, in the specific form of construction and combination and arrangement of parts and features shown in the drawing, which showing is only fragmentary and as one specific embodiment of the invention, are confined in a suitable race-way in the base frame B which has a central opening 3 communicating with the orifice of the hole F, and rests upon the surface of the ground. A suitable corresponding race-way is formed in the bottom of the table A. The drive means G consist, as to the member g, of a bevel gear 4 fixed upon one end of a shaft 5 journaled in a suitable bearing 6 supported upon the base frame B at one side thereof. The bevel gear 4 is accommodated within an annular channel 7 developed inwardly from the periphery of the table, beveled teeth 8 being formed or provided at the bottom of said channel and in mesh with the teeth of the bevel gear 4, and constituting the member h of the drive means G. Preferably the anti-friction devices b are disposed in a circular series extending beneath the bevel gear 4 and bevel teeth 8. The means E for uniting the table and the string in rotary couple may be of any preferred form, the nature of such means being not concerned in the present invention; and the same are shown in the drawing as comprising a bushing 9 disposed in the central opening in the table and surrounding the string portion D, the same having a top flange 10 overlying the upper surface of the table, and ribs or tongues 11 slidably fitting suitable vertical channels or grooves in the wall of the central opening in the table; said bushing having also slidable inter-locking engagement with the string portion D. The bushing 9 may readily be lifted from its place in the table, and restored to such working position; and the slidable connections at the tongues 11 and at the string portion D permit the string portion D to rise and fall as required in the development of the hole, which is accompanied by descent of the boring string therein.

The operation, method of use and advantages of the improved rotary well boring apparatus constituting the invention will be readily understood from the foregoing description, taken in connection with the accompanying drawing and following statement: Rotation is imparted to the table, so that it turns upon its anti-friction devices b, through the bevel gear 4 and the bevel teeth 8 which mesh therewith, such bevel teeth 8

being beneath the bevel gear. Any tendency of the teeth to slip or creep upon the teeth of the bevel gear will produce a lowering tendency of the table, instead of an elevating tendency, which latter is the case when the teeth 8 or the like are provided above the bevel gear 4, as at the top of the channel 7 within which the bevel gear is accommodated. Therefore, the table will be more effectively forced downwardly or held downwardly in its proper zone of rotation, upon the anti-friction devices b. It further results that no means *per se* are required to perform this holding down function, the necessity of such specific means being entirely eliminated by the construction and mode of application and operation of the drive means set forth. The anti-friction devices b, being disposed beneath the bevel teeth 8, in a circular series extending beneath the bevel gear 4, prevent any occurrence, should such be possible, of the surface of the table A being canted or tilted by downward pressure upon the same as the result of any tendency of the teeth 8 to creep upon the teeth of the bevel gear 4. This tendency is thus most effectually opposed and counteracted. While such location of the anti-friction devices is not deemed essential to the practice of the invention, it is illustrated and discussed as an added operative feature or advantageous factor which may or may not be employed as working conditions may suggest or require.

The provision of the features of improvement set forth result in a truer and more proper operation and performance of the table and coöperation of the same in the drive of the boring string which is rotatively coupled with the same; and wear of parts and damage, breakage, sticking or obstruction at various points in and throughout the string and rotating means therefor are materially provided against.

It is manifest that many variations may be made in details of construction and arrangement and combination of parts, members and features, in practising the invention, all with regard to the foregoing description and statement and disclosure in the drawing, without departing from a fair interpretation of the invention.

Having thus disclosed my invention, I claim and desire to secure by Letters Patent:

1. In rotary well boring apparatus, a rotation-imparting table, and common means for both rotating the table and holding the same down in proper plane of rotation; said means comprising teeth upon the table and a gear above the teeth and meshing therewith; said table teeth being provided within a channel extending around the table, and said gear being protectively disposed within said channel.

2. In rotary well boring apparatus, a ro-

tation-imparting table, and common means for both rotating the table and holding the same down in proper plane of rotation; said means comprising teeth upon the table and a gear above the teeth and meshing therewith; said table teeth being provided beneath a peripheral ledge upon the table and beneath which said gear is disposed.

In testimony whereof, I have signed my name to this specification in the presence of 10 two subscribing witnesses.

WILLIAM W. WILSON.
